UNITED STATES PATENT OFFICE.

WILLIAM CHURCHILL, OF CORNING, NEW YORK, ASSIGNOR TO CORNING GLASS WORKS, A CORPORATION OF NEW YORK.

DESIGN FOR A REFRACTING COVER-GLASS.

52,635.

Specification for Design.

Patented Nov. 12, 1918.

Application filed October 18, 1917. Serial No. 197,346. Term of patent 14 years.

To all whom it may concern:

Be it known that I, WILLIAM CHURCHILL, a citizen of the United States, residing at Corning, in the county of Steuben and State of New York, have invented a new, original, and ornamental Design for Refracting Cover-Glasses.

The figure in the accompanying drawing is a plan view of a refracting cover glass having my new design applied thereto.

I claim:

The ornamental design for a refracting cover glass as shown.

WILLIAM CHURCHILL.

Witnesses:

HENRY PHELPS GAGE,
EMILIO PASCUCCI.
